CLAIM

The ornamental design for a seat, as shown and described.

DESCRIPTION

FIG. 1 is a perspective view as seen from the front and upper left of a first embodiment of a seat showing my new design; FIG. 2 is a front elevational view thereof; FIG. 3 is a left side elevational view thereof, the right side is symmetrical; FIG. 4 is a top plan view thereof; FIG. 5 is a rear elevational view thereof; FIG. 6 is a perspective view as seen from the front and upper left of a second embodiment of the seat, wherein the sole difference from the first embodiment is the round tubular stock of the side frame members; FIG. 7 is a perspective view as seen from the front and upper left of the first embodiment of the seat, wherein the sole difference from FIG. 1 is in the environmental showing; and, FIG. 8 is a perspective view as seen from the front and upper left of the second embodiment of the seat, wherein the sole difference from FIG. 6 is in the environmental showing. The broken line showing of a seat member is for illustrative purposes only and forms no part of the claimed design.
